UNITED STATES PATENT OFFICE.

WILLIAM H. PURDY AND LEONARD C. PETERS, OF PROVIDENCE, RHODE ISLAND.

DESIGN FOR A SPOON, &c.

SPECIFICATION forming part of Design No. 24,228, dated April 23, 1895.

Application filed March 7, 1895. Serial No. 540,901. Term of patent 7 years.

To all whom it may concern:

Be it known that we, WILLIAM H. PURDY and LEONARD C. PETERS, citizens of the United States, residing at Providence, in the county of Providence and State of Rhode Island, have invented and produced a new and original Design for Spoons and other Similar Articles, of which the following is a specification, reference being had to the accompanying drawing, forming part thereof.

The drawing is a view of a spoon representing our new design.

The leading features of our design are a portrait - bust of Frederick Douglass surmounted by laurel branches on the upper portion of the handle of the spoon. In the bowl or ladle is the representation of a typical

southern log-cabin located in a clearing and the figure of a boy carrying across his shoulder a stick from which is suspended a bundle, and on the narrow portion of the spoon-handle, between the bowl and the upper portion of the handle, is the representation of a ladder.

What we claim is—

The design for a spoon or similar article substantially as herein shown and described.

In witness whereof we have hereunto set our hands.

WILLIAM H. PURDY.
LEONARD C. PETERS.

Witnesses:

JOSEPH H. MONROE,
JOHN T. GRIFFIN.
